Primary Examiner — Carla J Wright*(74) Attorney, Agent, or Firm* — Ersen IP (Nelson IP)(57) **CLAIM**

The ornamental design for a waterproof phone case, as shown and described.

DESCRIPTION

FIG. 1 is a perspective view of a waterproof phone case showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of the encircled region of FIG. 1; and,

FIG. 10 is an enlarged detail view of the encircled region of FIG. 2.

The dot-dash broken line circles in FIGS. 1-2 and 9-10 delineate portions of the waterproof phone case that are part of the claimed design and that are shown on an enlarged scale in FIGS. 9-10.
